FIRE EXTINGUISHER STANDPIPE

Filed April 5, 1926

FIG. 3.

Inventor:
Bernhard Reddemann
By Knight Bros,
Attns.

UNITED STATES PATENT OFFICE.

BERNHARD REDDEMANN, OF BERLIN-LICHTERFELDE, GERMANY, ASSIGNOR TO
PYRENE-MINIMAX CORPORATION, A CORPORATION OF DELAWARE.

FIRE-EXTINGUISHER STANDPIPE.

Application filed April 5, 1926, Serial No. 99,947, and in Germany April 6, 1925.

My invention relates to an extinguisher standpipe capable of being erected in front of a structure such as a tank or the like. It is frequently desirable to apply a jet pipe to the hearth of a fire from the ground without the use of ladders. This is, for instance, the case when a tank containing benzene, petrol or the like has caught fire. In the case of such fires it is not possible to place a ladder 10 against the tank in order to direct the squirting nozzle from it against the fire. In the case of certain extinguishing agents, for instance when employing foam it is, furthermore, not possible to project the extinguishing agent in form of a jet against the hearth of the fire, since on the one hand the target would easily be missed on account of the light foam being blown away by the wind and since on the other hand the jet of 15 foam becomes easily decomposed so that only individual flakes of foam reach the hearth of the fire which do not easily combine to form a continuous protective cover on the liquid to be protected.

20 These drawbacks are entirely eliminated by the extinguisher standpipe according to my invention. This standpipe preferably consists of a plurality of joined sections so that the pipeline may be shortened or lengthened as required. An auxiliary appliance consisting of a framework having a roller at its apex may be provided in order to facilitate erection of the pipe. Upon the pipe itself are mounted supports or legs which after the erection of the pipe are dug 25 into the ground at suitable angles. At its lower end the standpipe is provided with a counter-weight which preferably consists of a water box so that by varying the charge 30 of this box the magnitude of the balancing weight can be adapted to requirements. At its upper end the standpipe is preferably provided with a movable mouthpiece which may either be a nozzle or jet pipe or a foam descent pipe.

In the drawing affixed hereto an embodiment of my invention is illustrated by way of example.

In this drawing:

35 Fig. 1 is the improved standpipe erected for service in side-elevation,

Fig. 2 is a front elevation of the trestle employed for erecting the standpipe and for supporting the erected pipe, and

40 Fig. 3 is a view of the top part of a modi-

fied form of standpipe which is in this case provided with a movable and adjustable jet pipe.

Referring to the drawing, *a* is a tank projecting considerably above the ground and filled with an easily inflammable liquid fuel or the like. Over the top edge of this tank is passed the elongated standpipe *b* composed of a plurality of sections. In the adjusted position, the pipe *b* is secured by supports *c*, *c'* which in the drawing are shown one behind the other but in practice will preferably be placed side by side. These supports or legs are hinged to the pipe at their upper ends *d* and are at their lower ends provided with foot plate *e*, *e'* preventing them from penetrating too far into the soil, as well known. Instead of the two supports *e*, *e'* illustrated more than two, for instance three may be employed which after erection form 45 a pyramid. The angle of the supports with the ground depends upon the height to which the pipe *b* is to be carried up. The pipe rests apart from the supports *c*, *c'* also on the trestle *f* which may be provided with 50 side supports *g* and carries at its apex a roller *h*. For the purpose of bringing the pipe into position, it is first pushed obliquely across the roller *h* and carried upwards to the desired height whereupon the supports 55 *c*, *c'* are rammed into the ground. For further securing the pipe in its erected position, it may be provided with a strap *s* slidable longitudinally and adapted to be secured in position by a pressure or clamping screw *t* 60 and to be connected with the trestle *f* by chains *u*. To facilitate the erection of the pipe it is provided at its lower end at which a supply hose *i* can be attached with a water box *k* serving as counter-weight and furnished with a valve *l* for draining part of the water off and thus regulating the action of the counterweight. According to Fig. 1 of the drawing, a pipe *n* is attached by means of a hinge *m* upon the upper end of the pipe 65 *b* and hangs downwards. This pipe *n* is preferably closed at its lower end and provided with a number of openings *o* for the escape of the foam which are surrounded by cup-shaped structures *p* or dished flanges *q* running around the pipe. Usually the foam will issue from the lower openings of the tube *n* and thus slide from a small height down upon the burning liquid over the edge 70 of the cup-shaped structures. If, however 75

the pipe *n* dips into the contents of the tank *a* the foam issues from the openings *o* adjacent to the burning surface.

If the standpipe is intended to be used for squirting water or foam, it may be provided at its upper end with a nozzle or spray pipe *r*, as shown in Fig. 3, which is hinged or jointed at *m* and remains in any adjusted position.

10 It will be understood that modifications in the details may be made without departing from the principles and scope of my invention which should be judged in the light of prior knowledge.

15 I claim as my invention:

1. A device of the class described comprising in combination, a rigid pipe, a trestle having at its upper end a bearing adapted to slidably support said pipe intermediate its ends, and a plurality of anchoring and supporting legs hinged to said pipe at one side of said trestle.

2. A device of the class described comprising in combination, a rigid pipe, a trestle having at its upper end a bearing adapted to slidably support said pipe intermediate its

ends, a plurality of anchoring and supporting legs hinged to said pipe at one side of said trestle, and a variable counterweight on said pipe at the other side of said trestle. 30

3. A device of the class described comprising in combination, a rigid pipe, a trestle having at its upper end a bearing adapted to slidably support said pipe intermediate its ends, a plurality of anchoring and supporting legs hinged to said pipe at one side of said trestle, and a variable counterweight on said pipe at the other side of said trestle, comprising a tank adapted to contain liquid and having a drain valve in 35 the bottom thereof.

4. A device of the class described comprising in combination, a rigid pipe, a trestle having at its upper end a bearing adapted to slidably support said pipe intermediate its ends, a plurality of anchoring and supporting legs hinged to said pipe at one side of said trestle, a longitudinally adjustable strap on said pipe, and means for connecting said strap to said trestle. 45

In testimony whereof I affix my signature.

DR. BERNHARD REDDEMANN.
